MACHINE FOR PACKAGING STACKED HOL-
LOW WARE SUCH AS NESTED PAPER CUPS
OR THE LIKEWendell T. Burbank, Three Rivers, Mich., as-
signor to Sutherland Paper Company, Kala-
mazoo, Mich., a corporation of Michigan

Application January 13, 1949, Serial No. 70,652

13 Claims. (Cl. 53—88)

1

This invention relates to improvements in machines for packaging stacked hollow ware such as nested paper cups or the like.

The main objects of this invention are:

First, to provide a machine for packaging or wrapping hollow ware such as stacks of paper cups which results in a sealed wrapped package and eliminates or minimizes the handling of the unwrapped cups.

Second, and more specifically, to provide a machine for wrapping nested or stacked groups of tapered cup-like receptacles having bead-like rims and recessed bottoms.

Third, to provide a machine having these advantages and capacities which forms the wrappers from continuous webs of heat sealable wrapping material, the packages being delivered or discharged from the machine as complete individually wrapped packages.

Fourth, to provide a machine having these advantages which is of very large capacity.

Objects relating to details and economies of the invention will appear from the description to follow. The invention is defined and pointed out in the claims.

A preferred embodiment of the invention is illustrated in the accompanying drawing, in which:

Fig. 1 is a side elevational view of a machine embodying my invention with one side frame member removed, the shafts supported by the omitted side frame being sectioned.

Fig. 2 is an enlarged fragmentary plan view showing three complementary portions, the division lines being indicated by the lines A—A and B—B.

Fig. 3 is an enlarged fragmentary view mainly in vertical section on a line corresponding to line 3—3 of Fig. 2.

Fig. 4 is an enlarged fragmentary view in transverse section on a line corresponding to line 4—4 of Fig. 1.

Fig. 5 is an enlarged fragmentary view partially in vertical longitudinal section on a line corresponding to line 5—5 of Fig. 2.

Fig. 6 is an enlarged fragmentary transverse section on a line corresponding to line 6—6 of Fig. 5 with the grippers shown in actuated or gripping position by full lines and in retracted position by dotted lines.

Fig. 7 is an enlarged fragmentary view on a line corresponding to line 7—7 of Fig. 6.

Fig. 8 is an enlarged fragmentary view taken on a line corresponding to line 8—8 of Figs. 1 and 5 illustrating the relation of the crimper, seal-

2

ing and cutting means and of the holding and translating means.

Fig. 9 is an enlarged fragmentary view of the crimping, sealing and severing means taken on a line corresponding to line 9—9 of Fig. 10.

Fig. 10 is a fragmentary view on a line corresponding to line 10—10 of Fig. 9, showing further details of the crimping, sealing and severing means.

Fig. 11 is a plan view of one of the packages wrapped and sealed, but prior to the tucking of the ends of the wrapper into the bottom and top respectively of the packaged articles as is shown in Fig. 12.

Fig. 12 is a fragmentary view partially in longitudinal section of a completed package in association with a following package which serves as a means for tucking the wrapper into the top of a stack of receptacles.

The embodiment of my invention illustrated in the accompanying drawing is especially designed for the wrapping of stacks of paper cups, there being eight cups in each stack. It will be understood, however, that the machine is readily adapted for the wrapping of nested hollow ware of other shapes and dimensions and of other objects. In the accompanying drawing the frame is designated by the numeral 1. Referring to Fig. 1, only one side member of the frame is illustrated but it will be understood that the omitted side member is a substantial duplicate of that shown and that the side members are connected by suitable cross pieces and members to provide a rigid supporting frame for the various parts.

The stacks of receptacles to be wrapped are indicated by the numeral 2 and these illustrated are provided with outturned bead-like rims 3 and have inset or recessed bottoms 4. The cups are tapered so that they may be effectively nested or stacked as indicated in Fig. 12. The machine is designed to wrap the stacked or assembled groups of cups from a web of heat sealable wrapping material 5 such, for example, as cellophane, a roll of the material being shown at 6 supported by a suitable spindle 7 and provided with a friction brake 8 to prevent overrunning of the web as it is advanced step by step during the wrapping operations to be described.

The stacks of cups 2 are arranged in an inverted position to be fed by a conveyer including the conveyer belt 9, the upper reach of which is supported by the bar 10. This belt is supported by the driven pulley 11 and the pulley 12

to translate the stacks of cups to be individually discharged at the delivery end of the conveyer. The wrapping means comprises the trough-like transversely curved wrapping way 13 which is arranged with its forward end below the delivery 5 end of the feed conveyer. In the machine illustrated, this wrapping way is arranged in a forwardly inclined position but the main purpose of that is to bring the parts into convenient position for servicing and for removing the fully wrapped packages designated by the numeral 14, the wrapped packages being successively delivered to a trough-like support or holder 15 formed by rods from which they are commonly picked up to be packed in cartons.

The front end of the wrapping way 13 is positioned to receive the web from the guide roller 16. The wrapping way 13 has upwardly projecting curved folders 17 at its front end provided with rearwardly extending fingers or supporting arms 18. The U-shaped conforming member 19 depends into this folder 17 in closely adjacent but spaced relation thereto so that the web of paper passes between the conforming member and the wrapping member with the result that the web is conformed into an upwardly facing U-shape at the front end of the conveyer way 13 and it is maintained in this position by the outer fingers or arms 18 and the inner fingers or arms 20 until the stack of cups have been deposited thereon and until it reaches further folding or wrapping means adapted to turn the top of the wrapper inwardly around the package.

While the wrapper is held in this U-shape, as described, stacks of cups are delivered thereto in parallel relation to the way 13. This, in the embodiment illustrated, is accomplished by means of the delivery control arm or member 21 which is mounted on the rock shaft 22 and provided with stop fingers 23 and 24 which are adapted to alternately swing into and out of stop position through the slots 25 in the feed conveyer side members 26 (see Figs. 1, 3 and 4). When the stop arm 21 is actuated to discharge position or toward the right as viewed in Fig. 4, the stop 23 is retracted permitting a stack of cups to discharge downwardly over the guide 27 which also serves to support the members 20. This same discharging movement of the arm 21 positions the stop 24 to hold the work on the feed conveyer until the advance stack has been discharged and the arm 21 returned to again position the stop 23.

A stack of cups is shown in discharged position upon the web of wrapping material which has been conformed to U-shape on the conveyer way 13 (see Fig. 4). The work is positioned with the top facing forwardly, that is, forwardly relative to the front end of the machine. In this position the stack of cups and the wrapper conformed around the same in trough or channel shape is engaged by the work feed grippers 28 which are arranged in opposed pairs, these being provided with the vertical ribs 29 which are spaced to engage the wrapper between the rims of the cups. These feed grippers are carried by arms 30 on the rock shafts 31 which are not only mounted for rocking movement but also for axial movement by the bearings 32 and 33 carried by the rods 34 and 35 extending across the frame.

These shafts are provided with collars 36 engaged by the cross head 36 (see Fig. 4), which is connected by the link 37 to the actuating lever 38 pivotally supported by the shaft 39. This

lever is in turn actuated by the link 40 pivoted thereto at 41 and having a follower 42 engaging the cam groove 43 of the cam 44 (see Fig. 1). This rock shaft 39 has an arm 45 connected by the link 46 to an arm 47 on the rock shaft 22 carrying the stop member or feed control member 21 previously described. This insures that the parts be operated in timed relation.

The rock shafts 31 are rocked to actuate and retract the grippers 28 in properly timed relation by means of the pneumatic device designated generally by the numeral 48 and comprising the plunger indicated at 49 and the plunger rod 50 engaging the slots 51 in the arms 52 on the rock shafts 31.

A second pair of grippers 53 is the same as the grippers 28, being spaced therefrom, however, so as to grip the stack of receptacles that have been advanced one step by the grippers 28. This results in the feeding of the wrapping web and also the receptacles therein without displacement and with a proper spacing of the groups or stacks of receptacles. In Fig. 1 the grippers are shown in actuated position or at the limit of their rearward travel.

After the receptacles have been positioned in the web which has been conformed or folded to the upwardly facing U-shape, they are translated along the way 13 with the wrapper and below the top folder or wrapping member 54, which is adjustably supported by the arm 55 on the cross rod 56. This folder or wrapping member 54 is an outer folder or wrapping member and carries an inner wrapper folder, or wrapper supporting and guiding member 57 which extends rearwardly therefrom. Both these inner and outer members 54 and 57 are of downwardly facing curved channel section and they serve to fold and guide the edges of the wrapper inwardly as is shown in Fig. 2. This figure also shows the relation of the grippers. A yieldable transversely corrugated stop jaw 58 is provided at this position to insure that the package of cups is stopped in proper position to be gripped by the second pair of grippers.

The member 57 extends rearwardly and constitutes a guiding support for the edge portions of the wrapper as it is further folded in and wrapped around the stack of cups by third wrapping or folding unit designated generally by the numeral 59 (see Figs. 1 and 5). This unit comprises the rollers 60 carried by the supports or blocks 61 which are in turn carried by the arms 62 supported by posts 63.

These rollers contact the wrapper and are arranged in an inclined relation to the path of travel of the wrapper as shown in Fig. 2, so that they tend to wipe and further wrap the wrapper around the package until the edges are brought into overlapping relation as shown in Fig. 5, in which position they are subjected to the side sealer designated generally by the numeral 64. This side sealer is electrically heated, the details and the wiring, however, forming no part of this invention. It is sufficiently heated so that the overlapped side edges of the wrapper are sealed together as the stacks of cups and wrappers are positioned relative thereto as shown in Fig. 5.

The sealing unit 64 is carried by an arm 65 adjustably mounted on the rod 66. This permits the heating element being swung out of position when the machine is stopped and adjusted to the desired frictional engagement with the wrapper.

The ribs on the grippers 28 and 53 are so

spaced as to be positioned between the rims of the stack of cups when in gripping position and this results in an effective gripping of the cups and the wrapper and the translation of both with a step by step movement. To compensate for the step by step movement the web is supported in a loop 67 by means of the tensioning roll 68 on the pivoted arm 168 (see Fig. 1). The arm 168 has an adjustable counterweight 69. This permits a substantially uniform unwinding from the supply roll 6.

Spaced from the rear end of the wrapping way 13 and aligned therewith, is a delivery way 70 also of upwardly facing curved channel section. Opposed to the delivery way 70 is a curved friction plate 71 provided with flanges 72 opposed to flanges 73 on the way 70 and receiving the bolts 74 which are provided with tensioning springs 75. The way 70 is thus yieldably supported. An adjustable stop 76 limits the upward movement of the way 70. The packages which are sealed as they are delivered to the way 70 are frictionally held under compression by the springs 75.

The transfer grippers, designated generally by the numerals 77, are carried by arms 78 mounted on the rock shafts 31 carrying the feed or wrapping grippers previously described. The grippers 77 are provided with rubber covered longitudinally spaced curved fingers 79 and the stroke of the grippers 77 is such as to engage a stack of receptacles in the position shown in Fig. 5 in association with the side sealer. The same forward stroke engages the first set of grippers with the stack of receptacles that have been deposited upon the wrapper from the feed conveyer. The fully actuated or rearward position of the grippers 77 is shown by dotted lines in Fig. 5 and it will be seen that they carry the stack or assembly of receptacles into the delivery conveyer way.

Between the conveyer ways 13 and 70, the portions of the wrapper between spaced stacks or assemblies of receptacles being wrapped, is crimped and sealed at two spaced points and severed between the sealed points or zones. This crimping, sealing and severing assembly is designated generally by the numeral 80. It comprises opposed units designated generally by the numerals 81 and 82 (see Figs. 8, 9 and 10). These units are simultaneously operated transversely of the path of travel of the wrapper and the receptacles assembled therein.

The unit 81 is mounted on the plunger rod 83 projecting from the cylinder 84, the plunger 85 being shown at the right of Fig. 8. The fluid connections are shown at 86.

The unit 82 is provided with a similar supporting and actuating means and the fluid is simultaneously controlled by means not illustrated. The crimpers 87 are arranged in opposed telescoping pairs and have V-shaped recesses 88 terminating in circular notches or recesses 89 as shown in Fig. 8. The crimpers and the sealing and cutting members are carried by cross heads 90 supported on the reciprocating rods 91, the plungers being connected to the cross heads.

The sealing element 92 of the unit 81 is provided with spaced V-shaped members 93 while the sealing element 94 is provided with corresponding opposed recesses 95. The heating element 92 carries a knife 96 disposed between the portions 93, while the heating element 94 is provided with a recess 97 receiving the edge of the

knife in actuated position, the edges of the recess 97 in effect constituting shear bars for supporting the wrapper material for effective severing. The electrical connections are indicated at 98 (see Fig. 10).

With the parts thus arranged and after the machine has been operated to position one stack of cups, as shown at the left of Fig. 5, and another preceding stack within the delivery conveyer way, these crimping, sealing and severing units are simultaneously operated and the portions of the wrapper between the adjacent groups of receptacles are gathered or crimped by the crimpers 87 as is shown in Figs. 5 and 9. The gathered and crimped wrapper is sealed at two spaced points by the sealing elements and simultaneously severed between the sealing points or zones. The units 81 and 82 are then retracted in timed relation to the actuation of the transfer grippers which grip the stack of cups which has had the side thereof sealed and transfer it to the delivery conveyer way and into thrust translating engagement with the preceding assembly.

This results in tucking the sealed end 99 of the individual wrapper 100 (see Figs. 11 and 12) into the recessed bottom of the cup stack or assembly and the end 101 is tucked into the top receptacle of the stack as is shown in Fig. 12. As stated, the cups are discharged from the delivery conveyer into the trough 15 from which they are removed by the operator or they might be delivered upon a conveyer belt or the like or into a receptacle.

The side sealer or heating element 64 is provided with a thermostat conventionally illustrated at 113. The thermostat for the heating elements 103 are not illustrated. The transverse crimping, sealing and cutting units are controlled from a control valve shown conventionally at 104 which is operated in timed relation to other operations by means of the cam 105 (see Fig. 1). The connections, as stated, are not illustrated because they form no part of the invention.

The machine is driven from the motor 106 which is connected by the belt 107 and a pulley 108 to the shaft 109 which is in turn connected by the sprocket chain 110 to the shaft 111 on which the cam 114 is mounted. A hand wheel 112 is provided on the shaft 109 to provide hand operation for threading the machine. The shaft 113, on which the feed conveyer pulley 11 is mounted, is connected by the belt 114 to the shaft 111.

It will be understood that the gripper actuating unit 48 is operated in timed relation to the other mechanisms to perform their several functions in proper sequence. I have not described in detail various mountings and supports for the several parts and mechanisms as such details form no part of my present invention, and providing suitable supports is believed to be within the skill of the art. Also, I have not attempted to illustrate certain welds or describe certain welded joints or bolt or screw connections for the same reasons.

I have illustrated and described my invention in a highly practical commercial embodiment thereof and, as stated, especially designed for the wrapping of tapered cup-like receptacles. My invention may, however, be readily adapted for wrapping other forms of stacked receptacles or other hollow ware and other objects. The machine of my invention is of large capacity and entirely automatic in operation after it is

properly threaded and manipulated to position the work to be grasped by the feed or translating grippers.

Having thus described my invention, what I claim as new and desire to secure by Letters Patent is:

1. In a machine for wrapping nested assemblies of hollow receptacles having outturned rims and recessed bottoms, the combination of an upwardly facing trough-like wrapping way, opposed curved inwardly facing outer side folders disposed at the front end of and complementing said wrapping way and having rearwardly extending outer wrapper supporting arms, an inner former and wrapper support folder cooperating with said way and said opposed side folders and spaced therefrom permitting the passage of a wrapper web therebetween and having inner web supporting arms opposed to and spaced from said outer supporting arms, a transversely curved downwardly facing top folder disposed at the rear of said supporting arms, a transversely curved top former and wrapper support opposed to and extending rearwardly from said top folder in supporting relation to the edges of the wrapper translated therealong, a yieldable transversely ribbed stop member disposed below said top former to successively engage the assemblies to be wrapped, rear folders operatively associated with the rear end of said top former to cooperate therewith in conforming and guiding the wrapper into a tubular form with overlapping edges, means for discharging assemblies of receptacles sidewise between said inner web supporting arms in spaced relation upon the wrapper, pairs of opposed feed grippers actuated for simultaneous closing and opening for gripping and releasing the assemblies through the wrapper and for simultaneous reciprocation for translating the spaced assemblies and the wrapper along the wrapping way step by step, a side sealer disposed at the rear of the rear folders in coacting relation to the overlapped longitudinal edges of the wrapper, a delivery conveyer way disposed in rearwardly spaced aligned relation to the wrapping way, a friction plate disposed in opposed relation to the delivery way for frictionally retarding the movement of the wrapped assemblies thereon, means for crimping, sealing and severing the wrapper between said wrapping and delivery ways, and a pair of transfer grippers actuated in timed relation with the feed grippers to engage an assembly at the rear of the wrapping way and transfer it to the delivery way, said several grippers being provided with projecting grip portions engaging the wrapper between the rims of nested receptacles to facilitate translation of the assemblies and wrapper together, said delivery conveyer and coacting friction plate frictionally retarding the wrapped and sealed assemblies thereon so that an assembly delivered by the transfer grippers is nested with the last preceding assembly and the trailing sealed end of the wrapper of said preceding assembly is tucked into the trailing receptacle thereof.

2. In a machine for wrapping nested assemblies of hollow receptacles having outturned rims, the combination of an upwardly facing trough-like wrapping way, opposed side folders disposed at the front end of said wrapping way and hav-

ing rearwardly extending outer wrapper supporting arms, an inner wrapper former and wrapper support folder cooperating with said way and said opposed side folders and spaced therefrom permitting the passage of a wrapper web therebetween and having inner web supporting arms opposed to and spaced from said outer supporting arms, a transversely curved downwardly facing top folder disposed at the rear of said supporting arms, a transversely curved top former and wrapper support opposed to and extending rearwardly from said top folder in supporting relation to the edges of the wrapper translated therealong, a yieldable stop member disposed below said top former to successively engage the assemblies to be wrapped, a rear folder means associated with said top former to cooperate therewith in conforming and guiding the wrapper into a tubular form with overlapping edges, means for discharging assemblies of receptacles sidewise in spaced relation upon the wrapper, pairs of opposed feed grippers actuated for simultaneous gripping and releasing the assemblies and wrapper and for simultaneous reciprocation for translating the spaced assemblies and the wrapper along the wrapping way step by step, a sealer disposed at the rear of the rear folders in coacting relation to the overlapped longitudinal edges of the wrapper, a delivery conveyer way disposed in rearwardly spaced aligned relation to the wrapping way, a friction plate disposed in opposed relation to the delivery way for frictionally retarding the movement of the wrapped assemblies thereon, means for sealing and severing the wrapper between said wrapping and delivery ways, and a pair of transfer grippers actuated in timed relation with the feed grippers to transfer an assembly from the wrapping way to the delivery way, said several grippers being provided with projecting grip portions engaging the wrapper between the rims of nested receptacles to facilitate translation of the assemblies and wrapper together, said delivery conveyer and coacting friction plate frictionally retarding the wrapped and sealed assemblies thereon so that an assembly delivered to the delivery conveyer is nested with the last preceding assembly and the trailing sealed end of the wrapper of said preceding assembly is tucked into the trailing receptacle thereof.

3. In a machine for wrapping nested assemblies of hollow receptacles having outturned rims, the combination of an upwardly facing trough-like wrapping way, opposed side folders disposed at the front end of said wrapping way, an inner wrapper former cooperating with said way and said opposed side folders, a top folder disposed at the rear of said side folders, a top former and wrapper support extending rearwardly from said top folder in supporting relation to the edges of the wrapper translated therealong, a yieldable stop member disposed below said top former to successively engage the assemblies to be wrapped, a rear folder means associated with said top former to cooperate therewith in conforming and guiding the wrapper into a tubular form with overlapping edges, means for discharging assemblies of receptacles sidewise in spaced relation upon the wrapper, pairs of opposed feed grippers actuated for simultaneous gripping and releasing the assemblies and wrapper and for simultaneous reciprocation for translating the spaced assemblies and the wrapper along the wrapping way step by step, a sealer disposed at the rear of the rear folders in coacting relation

to the overlapped longitudinal edges of the wrapper, a delivery conveyer way disposed in rearwardly spaced aligned relation to the wrapping way, a friction plate disposed in opposed relation to the delivery way for frictionally retarding the movement of the wrapped assemblies thereon, means for sealing and severing the wrapper between said wrapping and delivery ways, and a pair of transfer grippers actuated in timed relation with the feed grippers to transfer an assembly from the wrapping way to the delivery way, said several grippers being provided with projecting grip portions engaging the wrapper between the rims of nested receptacles to facilitate translation of the assemblies and wrapper together, said delivery conveyer and co-acting friction plate frictionally retarding the wrapped and sealed assemblies thereon so that an assembly delivered to the delivery conveyer is nested with the last preceding assembly and the trailing sealed end of the wrapper of said preceding assembly is tucked into the trailing receptacle thereof.

4. In a machine for wrapping nested assemblies of hollow receptacles, the combination of an upwardly facing trough-like wrapping way, opposed outer side folders disposed at the front end of said wrapping way and having rearwardly extending outer wrapper supporting arms, an inner wrapper former and wrapper support folder cooperating with said way and said outer side folders and spaced therefrom permitting the passage of a wrapper web therebetween and having inner web supporting arms opposed to and spaced from said outer supporting arms, a transversely curved downwardly facing top folder disposed at the rear of said supporting arms, a transversely curved top former and wrapper support opposed to and extending rearwardly from said top folder in supporting relation to the edges of the wrapper translated therealong, a rear folder means associated with said top former to cooperate therewith in conforming and guiding the wrapper into a tubular form with overlapping edges, means for discharging assemblies of receptacles sidewise in spaced relation upon the wrapper, pairs of opposed feed grippers actuated for simultaneous gripping and releasing the assemblies and wrapper and for simultaneous reciprocation for translating the spaced assemblies and the wrapper along the wrapping way step by step, a sealer disposed at the rear of the rear folder means in coacting relation to the overlapped longitudinal edges of the wrapper, a delivery conveyer way disposed in rearwardly spaced aligned relation to the wrapping way, means for sealing and severing the wrapper between said wrapping and delivery ways, and a pair of transfer grippers actuated in timed relation with the feed grippers to transfer an assembly from the wrapping way to the delivery way.

5. A wrapping machine of the class described comprising in combination, a feed conveyer for feeding nested assemblies of hollow ware in inverted position, a trough-like wrapping way disposed with its forward end below the delivery end of said conveyer, side folders disposed at the sides of the wrapping way and acting to turn the sides of a wrapper web upwardly into a trough-like form, inner and outer wrapper supports disposed at the rear of said side folders, a top folder disposed at the rear of said wrapper supports for turning the edges of the wrapper web inwardly, a top former disposed to support such inturned edges of the wrapper web, rear folders cooperating with said former to position the edges of the wrapper in overlapping relation, a side sealer for sealing portions of such overlapping edges, means for discharging assemblies to be wrapped from said feed conveyer in spaced relation upon the wrapper, feed grippers for translating assemblies and wrapper along the wrapping way with step by step movement, a delivery conveyer way disposed in spaced relation to said wrapping way and provided with means

folders cooperating with said former to position the edges of the wrapper in overlapping relation, a side sealer for sealing portions of such overlapping edges, means for discharging assemblies to be wrapped from said feed conveyer in spaced relation upon the wrapper, feed grippers for translating assemblies and wrapper along the wrapping way with step by step movement, a delivery conveyer way disposed in spaced relation to said wrapping way and provided with means for frictionally retarding the translation of the work thereon, means for crimping, sealing and severing the wrapper between said wrapping and delivery ways, and transfer grippers actuated in timed relation with said feed grippers to transfer an assembly having the wrapper therearound and sealed at its leading end to said delivery way and into nested relation to the last preceding assembly on the delivery way whereby the trailing sealed end of the wrapper of said preceding assembly is tucked into the trailing receptacle.

6. A wrapping machine of the class described comprising in combination, a trough-like wrapping way, side folders disposed at the sides of the wrapping way and acting to turn the sides of a wrapper web upwardly into a trough-like form, inner and outer side wrapper supports disposed at the rear of said side folders, a top folder disposed at the rear of said side supports for turning the edges of the wrapper web inwardly, a top former disposed to support such inturned edges of the wrapper web, rear folders cooperating with said former to position the edges of the wrapper in overlapping relation, means for discharging assemblies to be wrapped in spaced relation upon the wrapper, feed grippers for translating assemblies and wrapper along the wrapping way with step by step movement, a delivery conveyer way disposed in spaced relation to said wrapping way and provided with means for frictionally retarding the translation of the work thereon, means for crimping, sealing and severing the wrapper between said wrapping and delivery ways, and transfer grippers actuated in timed relation with said feed grippers to transfer an assembly having the wrapper therearound and sealed at its leading end to said delivery way and into nested relation to the last preceding assembly on the delivery way whereby the trailing sealed end of the wrapper of said preceding assembly is tucked into the trailing receptacle.

7. A wrapping machine of the class described comprising in combination, a feed conveyer for feeding nested assemblies of hollow ware in inverted position, a trough-like wrapping way disposed with its forward end below the delivery end of said conveyer, side folders disposed at the sides of the wrapping way and acting to turn the sides of a wrapper web upwardly into a trough-like form, a top folder disposed at the rear of said side folders for turning the edges of the wrapper web inwardly, a top former disposed to support such inturned edges of the wrapper web, rear folders cooperating with said former to position the edges of the wrapper in overlapping relation, a side sealer for sealing portions of such overlapping edges, means for discharging assemblies to be wrapped from said feed conveyer in spaced relation upon the wrapper, feed grippers for translating assemblies and wrapper along the wrapping way with step by step movement, a delivery conveyer way disposed in spaced relation to said wrapping way and provided with means

for frictionally retarding the translation of the work thereon, means for crimping, sealing and severing the wrapper between said wrapping and delivery ways, and transfer grippers actuated in timed relation with said feed grippers to transfer an assembly having the wrapper therearound and sealed at its ends to said delivery way and into nested relation to the last preceding assembly on the delivery way whereby the trailing sealed end of the wrapper of said preceding assembly is tucked into its trailing receptacle.

8. A wrapping machine of the class described comprising in combination, a trough-like wrapping way, side folders disposed at the sides of the wrapping way and acting to turn the sides of a wrapper web upwardly into a trough-like form, a top folder disposed at the rear of said side folders for turning the edges of the wrapper web inwardly, a top former disposed to support such inturned edges of the wrapper web, rear folders cooperating with said former to position the edges of the wrapper in overlapping relation, means for discharging assemblies to be wrapped in spaced relation upon the wrapper, feed grippers for translating assemblies and wrapper along the wrapping way with step by step movement, a delivery conveyer way disposed in spaced relation to said wrapping way and provided with means for frictionally retarding the translation of the work thereon, means for crimping, sealing and severing the wrapper between said wrapping and delivery ways, and transfer grippers actuated in timed relation with said feed grippers to transfer an assembly having the wrapper therearound and sealed at its ends to said delivery way and into nested relation to the last preceding assembly on the delivery way whereby the trailing sealed end of the wrapper of said preceding assembly is tucked into its trailing receptacle.

9. A wrapping machine for wrapping hollow ware comprising a feed conveyer for feeding the work in inverted position, a wrapping way disposed with its forward end below the delivery end of the conveyer and adapted to support a wrapper web of heat sealable material, side folders disposed at the sides of the wrapping way and acting to turn the wrapper web upwardly into a trough-like form, a top folder for turning the edges of the web inwardly, a top former disposed to support such inturned edges of the web, rear folders cooperating with the former to position the edges of the web in overlapping relation, a heat sealer for sealing portions of such overlapping edges, means for discharging assemblies to be wrapped from said conveyer onto the wrapping web with the hollow ware of the assembly opening forwardly while the web is supported in trough-like form and in timed relation to the translation of the web whereby the assemblies are spaced on the web, means for translating the assemblies and the web along the wrapping way acting to grip the assemblies and web simultaneously, means positioned between said way and said receiver for crimping, sealing and severing the web in timed relation to the actuation of said feed means and between said assemblies, a receiver positioned in spaced relation to the rear of said wrapping way and adapted to receive wrapped assemblies and restrain the same against further rearward motion, means for transferring assemblies from said wrapping way to said receiver with the rear end of the wrapper sealed and into internested relation with the preceding assembly whereby the assemblies are nested in the receiver and the trailing end of the preceding

wrapper is tucked into the rear receptacle of the assembly.

10. A wrapping machine for wrapping hollow ware comprising a wrapping way adapted to support a wrapper web of heat sealable material, side folders disposed at the sides of the wrapping way and acting to turn the wrapper web upwardly into a trough-like form, a top folder for turning the edges of the web inwardly, a top former disposed to support such inturned edges of the web, rear folders cooperating with the former to position the edges of the web in overlapping relation, a heat sealer for sealing portions of such overlapping edges, means for translating the assemblies and the web along the wrapping way acting to grip the assemblies and web simultaneously, means positioned between said way and said receiver for crimping, sealing and severing the web in timed relation to the actuation of said feed means and between said assemblies, a receiver positioned in spaced relation to the rear of said wrapping way and adapted to receive wrapped assemblies and restrain the same against further rearward motion, means for transferring assemblies from said wrapping way to said receiver with the rear end of the wrapper sealed and into internested relation with the preceding assembly whereby the assemblies are nested in the receiver and the trailing end of the preceding wrapper at the open end of the ware in each assembly is tucked into the trailing receptacle of the assembly.

11. A wrapping machine of the class described for wrapping hollow work comprising a wrapping way, folders associated with said wrapping way to turn the sides of a web of wrapping material upwardly into a trough-like form as the web is translated along the way, a top folder associated with the way for turning the edges of the wrapper inwardly as it is translated along the way, a top former supporting such inturned edges of the wrapper, means cooperating with said top former to conform the wrapper into a tube with overlapping edges, a sealing means for such overlapping edges, means for delivering work to be wrapped upon the wrapper in timed relation to the translation thereof so that the work is spaced upon the wrapper, means for translating the work and the wrapper along the wrapping way with a step by step movement and acting to grip the work and the wrapper for simultaneous movement, a delivery conveyer way disposed in spaced relation to the wrapping way and having means associated therewith for frictionally retarding the translation of work thereon, means for crimping, sealing and severing the wrapper between said ways and between the work within the wrapper, and transfer means actuated in timed relation with the wrapping way work translating means to transfer work having the wrapper therearound sealed at its trailing end to said delivery way and into nested relation with the last preceding wrapped work on the delivery way whereby the trailing sealed end of the wrapper of said preceding wrapped work is tucked into the work.

12. A wrapping machine of the class described for wrapping hollow work comprising a wrapping way, folders associated with said wrapping way to turn the sides of a web of wrapping material upwardly into a trough-like form as the web is translated along the way, a top folder associated with the way for turning the edges of the wrapper inwardly as it is translated along the way, a top former supporting such inturned edges of the wrapper, means cooperating with said top former

to conform the wrapper into a tube with overlapping edges, means for translating the work and the wrapper along the wrapping way with a step by step movement, a delivery conveyer way disposed in spaced relation to the wrapping way and having means associated therewith for frictionally retarding the translation of work thereon, means for crimping, sealing and severing the wrapper between said ways and between the work within the wrapper, and transfer means actuated in timed relation with the wrapping way work translating means to transfer work having the wrapper therearound sealed at its trailing end to said delivery way and into nested relation with the last preceding wrapped work on the delivery way whereby one sealed end of the wrapper of one wrapped piece of work is tucked into the hollow end of the work.

13. A wrapping machine for wrapping hollow ware comprising, a wrapping way adapted to support a web of heat sealable wrapping material with a portion of the web in U-shaped trough-like form, means for discharging nested assemblies of hollow ware into said portion of said web in aligned relation, means including transversely and longitudinally movable grippers positioned to grip successive assemblies through said web and advance both the web and the assembly, said grippers having projecting tooth portions spaced equally to the spacing of the ware in the assemblies and engageable with said web portions between the nested ware of said assemblies, said means for discharging assemblies and said grippers being connected to operate in timed relation, the longitudinal movement of said grippers being

longer than the length of said assemblies whereby a substantial length of the web is provided between successive assemblies, means positioned adjacent said way and operative to wrap said wrapper around said assemblies and to seal portions of the wrapper, means positioned in longitudinally spaced relation from the end of said way and the advanced position of said grippers for crimping, sealing and severing the web between successive assemblies, the severing means being positioned longitudinally with respect to the end of the assembly engaged by said grippers to engage and act upon the web between successive assemblies at a point closer to the closed end of one assembly than the open end of the adjacent assembly, and means for removing the leading assembly from the end of the way after the web is severed.

WENDELL T. BURBANK.
